UNITED STATES PATENT OFFICE.

JOHN M. CULVER, OF NEWBURYPORT, MASSACHUSETTS.

DESIGN FOR A HANDLE FOR SPOONS AND LIKE ARTICLES.

SPECIFICATION forming part of Design No. 18,458, dated July 17, 1888.

Application filed April 5, 1888. Serial No. 269,761. Term of patent 7 years.

To all whom it may concern:

Be it known that I, JOHN M. CULVER, a citizen of the United States, residing at Newburyport, county of Essex, and State of Massachusetts, have invented and produced a new and original Design for Handles of Spoons and Like Articles, of which the following is a specification, reference being had to the accompanying drawing, forming part thereof.

10 The drawing shows my newly-designed handle applied to a spoon.

The handle A, near the middle of its length, has a medallion, a, of oval shape, composed of a plain band and an oval-shaped row of dots, 15 the medallion being in a corrugated field, b, terminated by a row of dots, c, and a cross-band, d. The broad part or end of the handle from the band d toward the end of the handle has displayed upon it a wedge-shaped figure, 20 e, arched at top, as at e', and having dentils e', the ground of the said figure containing a

shell, f, and two fan-like figures, g, the stems of the fan-like figures having at their sides trefoils h. Below the band d' is the vine-like figure m.

25 The leading feature of my design consists in the figure e with the shell and fan-like figures therein.

I claim—

The design for a handle, consisting of the wedge-shaped figure e, containing the shell and fan-like figures g, trefoils h, the medallion on the corrugated ground, vine-like figure m, and cross-bars d d', as shown.

In testimony whereof I have signed my name 35 to this specification in the presence of two subscribing witnesses.

JOHN M. CULVER.
